AUTOMATIC DEHYDRATION APPARATUS
FOR CEREALS

William A. Noel, Washington, D. C., assignor of
one-third to John N. Joerger and one-third to
Robert C. King, both of Washington, D. C.

Application July 5, 1949, Serial No. 103,033

2. Claims. (Cl. 34—54)

1.

This invention relates to an automatically controlled apparatus for dehydrating cereals.

An object of the invention is the provision of an apparatus having a normally closed circuit containing cereals through which is forced heated air for removing moisture therefrom, the air being circulated continuously through the grains at a predetermined temperature until the moisture content of said air reaches a predetermined degree whence the greater portion of the saturated air is withdrawn from the closed circuit with a fresh supply of air being admitted thereto and heated to continue the dehydrating process and to compensate for the loss of the saturated air.

Another object of the invention is the provision of an apparatus which is automatically controlled for dehydrating the cereals by hot air forced through the cereals in a closed circuit with means for withdrawing humid hot air from the circuit while supplying sufficient fresh dry air to the circuit to maintain substantially a continuous dehumidifying process for the cereals.

A further object of the invention is the provision of an apparatus for removing excess moisture from grains prior to storage, said apparatus including a normally closed circuit in which is stored a mass of grain and through which a continuous circulation of hot air is maintained until said air reaches a degree of saturation whence a hygrostat will cause an exhaust fan to be set in operation for removing progressively the saturated air, means being employed at this time for supplying fresh air to the circuit to obtain a resulting mixture therein that has been conditioned for a normal humidifying process, the cycle continuing in an open and closed circuit until the evaporation becomes substantially constant and the exhaust periods comparatively infrequent.

The invention will be best understood from a consideration of the following detailed description in connection with the accompanying drawings, nevertheless, it must be borne in mind that the invention is not confined to the disclosure but is susceptible of such changes and modifications as shall define no material departure from the salient features of the invention as expressed in the appended claims.

In the drawings:

Figure 1 is a longitudinal vertical section of my dehumidifier taken along the line 1—1 of Figure 2;

Figure 2 is a plan view of the dehumidifier with parts in section;

Figure 3 is a rear end view in elevation of the dehumidifier;

2.

Figure 4 is an enlarged fragmentary vertical section taken along the line 4—4 of Figure 3 showing more in detail a hinged door provided with automatically operated louvers in connection with an exhaust fan;

Figure 5 is an enlarged vertical section of a hygrostat for setting in operation the exhaust fan and a motor for opening and closing the louvers associated with said fan;

Figure 6 is an enlarged end view of the hygrostat which is at right angles to the section illustrated in Figure 5;

Figure 7 shows more or less diagrammatically electric circuits for controlling various operating mechanism of the humidifier; and

Figure 8 is a fragmentary transverse vertical section taken along the line 8—8 of Figure 1.

Referring more particularly to the drawings, 10 and 10a designate sections of a concrete base upon which is mounted a rectangularly shaped housing 11 having a gable roof 12. The base has a centrally disposed longitudinal channel or drag pit 13 to receive the cereals after they have been dehumidified sufficiently. The upper faces 14 of the base at each side of the channel are inclined downwardly towards the channel so that the cereals will roll into said channel as will be explained presently, for removal by a conveyor not shown. The opposite ends of the drag pit or channel 13 are closed by hinged doors 15 but are opened during removal of the cereal.

The floor of the housing is formed of a plurality of perforated metal plates 18 which extend longitudinally of the housing and in close association with each other to prevent the cereal being treated from falling into the channel 13 and onto the inclined faces 14 of the top of the sections of the base member. It will be noted from Figure 1 that the plates are supported by transverse bars 19 which in turn are carried by the upper portions of the base member. The channel 13 and the spaces between the inclined faces 14 and the perforated plates 18 provide air passages as will be explained presently. The plates 18 are movable to discharge the grain into the channel 13 from the housing 11, upon opening of the doors 15 and employing a suitable tool such as a crow-bar for displacing the plates by an upward pressure. The intermediate portions of the bars 19 at each side of the pit or channel 13 may be provided with feet 20 resting on the inclined faces of the sections 10 and 10a of the base member for supporting the plates 18.

The housing 11 includes a pair of parallel side

walls 21 and 22 and end walls 23 and 24 which have the respective gables 25 and 26. The rear end wall has a pair of openings 27 closed by doors 28. It will be noted from Figures 1 and 2 that the peripheries of the openings 27 are beveled to correspond to the complementary beveling of the peripheries of the doors 28 so that when the doors are closed they will seal the openings against the loss of air. The doors are retained in closed position by any well known means. The gable 25 of the front end wall 23 has an opening 30 for a purpose which will be explained presently.

A rectangular door 31 hinged as at 31' closes normally an opening 32 in the gable 26 at the upper end of the rear wall 24. The peripheries of said opening and door are beveled complementary to provide an airtight fit. The door is in the form of a frame having a central opening which is closed normally by a plurality of louvers 33 of well known construction. These louvers are fixed to shafts 34 and are swingable in the opening in the door with the free edges thereof adapted to be moved outwardly as indicated by the dotted lines in Figure 4. The shafts have the usual cranks connected together by an operating rod 35 (Figure 7) which is shifted in one direction by a motor 36 in a circuit 37 which is parallel to the circuit 38a of a motor 38 for operating an exhaust fan 40 enclosed by a protective screen 40a and associated with the door 31. The louvers close by gravity when the motor 36 is cut off.

A hygrostat designated generally by the numeral 41 (Figure 1) closes the circuits to the motors 36 and 38 when the moisture in the atmosphere in the housing reaches a predetermined degree. The hygrostat shown more particularly in Figures 5 and 6 includes a supporting base 42 attached to the side wall 21. Spaced pairs of parallel brackets 43 rising from said base form guides for superimposed strips of basswood 44. The contacting faces of the strips have aligned semi-circular grooves 45 to permit the circulation of air therethrough. The opposite ends of each strip are cut away to provide pairs of vertical notches 46 to receive the adjacent side edges of the brackets which act as guides for the expanding strips. A bolt 47 threaded into a passage in the base 42 has its upper free end in engagement with the lowermost strip 44a of the basswood. The bolt may be screwed in opposite directions for adjustably positioning the uppermost strip at various horizontal levels.

A mercury switch is designated generally by the numeral 50. This switch consists of a hermetically sealed glass tube 51 having a predetermined quantity of mercury 52 therein. Spaced contacts 53 and 54 project into the tube. A rod 55, rigid with the inner end of the tube, has its free end provided with a passage to receive a pin 56 screwed into the wall 21. As long as the bulb 51 is in the position shown in Figure 5 the circuit to the motors 36 and 38 are open. However, when the moisture content of the air in the housing rises sufficiently, the strips 44 will expand and raise the bulb so that the mercury therein will cover the contacts 53 and 54 and close the circuits to the motors.

A casing 60 is mounted on a concrete base 61 at one side of the front end 23 of the housing 11 with the longitudinal centers of the casing and housing being in alignment (Figure 2). A conduit 62 sealed at one end to the passage 30 has its other end in communication with a blower housing 63, the blower therein being revolved by

an electric motor 64 by means of a belt or chain 65 and the necessary pulleys.

A heater 66 is mounted in a conduit 67 having a reduced end 68 which merges into the blower housing 63. The other end of the conduit is closed except for an elongated passage 70. A tapered conduit 71 which has its larger area at the passage 70 extends from said passage to and through the wall 23 of the housing 11 where it enters into the space between the perforated plates 18 and the tops of the sections 10 and 10a of the base member for the housing 11. This reduced end 72 discharges air also into the channel 13. The conduit 71 is so formed that air pressure is built up at the reduced end 72 whence the air enters the channel 13 and into the space below the perforated plates at an increased rate of speed. The heater is controlled by a valve 73 operated by a motor 74 (Figure 7). The motor in turn is in a circuit with a thermostat 75 (Figures 1 and 7) carried by an intermediate transverse bar 19. The thermostat controls in effect the temperature of the air forced by the blower through the cereals stored in the housing 11.

Referring more particularly to Figures 1 and 2, it will be seen that the conduit 62 communicates with a horizontal conduit 80 which leads directly into the center of the blower housing 63 so that air from the housing 11 is drawn into the housing 63 and recirculated upwardly through the cereals in the housing 11. A valve 81 normally closes the outer open end of the conduit 80 but is opened to admit fresh air to the blower housing and this air is mixed with a portion of the air in the housing 11 when the louvers 33 are open and the fan 40 is exhausting the moisture-laden air from the housing. The valve 81 is operated by a small motor 82 which is in a circuit 83 parallel with the exhaust fan circuit 38a.

It will be noted that the housing or hopper 11 together with the conduits 62 and 80, the blower housing 63, the conduits 67 and 71 and the channel 13 form a closed circuit through which the air heated by the burner 66 is recirculated constantly. The cereal, whether corn, rye or wheat, is supplied to the housing 11 through the opening 32 which is normally closed by the door 31 and the louvers 33. The grain is supported by the perforated plates 18 and the heated air is forced through the grain until approximately ten percent of the moisture content is left in the grain. The temperature of the air is maintained at approximately 180° F. It will be appreciated that at this temperature, all insect life will be destroyed since a temperature of 140° F., if maintained for ten minutes, is sufficient to destroy insects.

During the continuous circulation of the heated air through the cereal, the air becomes saturated with moisture from the cereal and the hygrostat 41 closes the circuits to the motors 36, 38 and 82 whence the louvers 33 are opened and the exhaust fan is operated for forcing the moisture-laden air from the housing or hopper 11. At the same time, the valve 81 is opened to admit fresh air to the blower housing 63. This fresh air is mixed with the saturated air in the housing.

The thermostat 75 controls the burner 66 at all times to maintain the temperature of the air at approximately 180° F. However, when the cooler fresh air is admitted by the valve 81, the thermostat closes the circuit to the motor 74 which opens the valve 73 of the burner so that the air will be heated to the proper tempera-

ture. When the moisture content of the air drops to a predetermined degree, the exhaust fan 40 is cut off and the motor 36 stops whence the louvers 33 fall by gravity into closed position. The circuit to the motor 82 is now open and the fresh air valve 81 will be closed either by gravity or by a spring.

The hygrometer is adjusted by the bolt 47 to start the exhaust fan at a selected degree of humidity in the air. During the exhausting and the supplying of fresh air, the apparatus is working in an open circuit and such circuit is continued until the air has been conditioned to a proper drying temperature and to a satisfactory degree of humidity. The cycle continues in an open and closed manner until the relative humidity of the air is such that the fan 40 will be operated less frequently and the recirculation of the air will be maintained in a closed circuit for longer periods.

What I claim:

1. An apparatus for dehumidifying a cereal comprising a base provided with an upwardly open longitudinal channel, a housing mounted on the base above said channel, movable means for closing the opposite ends of the channel, said means adapted to be opened for the removal of the cereal when discharged into the channel, transverse supports above the channel a floor having perforated movable sections positioned on said transverse supports for supporting the cereal above the base and channel, the channel and the space between the floor and base forming an air chamber, an air heater located externally of the housing, a blower, a casing enclosing the heater and connecting the blower with the air chamber below the perforated floor and including a tube having a reduced end leading directly into said air chamber, an air return conduit connecting the top of the housing with the blower, means for causing air to be exhausted from the housing, means located in the housing in the path of the air entering the return conduit controlling the last mentioned means when the saturation of the water vapor in the air has reached a predetermined degree, the cereal being stored on the perforated floor so that the heated air is forced upwardly through said cereal to remove moisture, the floor sections being movable to discharge the cereal into the channel for removal therefrom.

2. An apparatus for dehumidifying a cereal comprising a base provided with an upwardly open longitudinal channel, a housing mounted on the base above said channel, movable means for closing the opposite ends of the channel, said means adapted to be opened for the removal of the cereal when discharged into the channel, transverse supports above the channel a floor having perforated movable sections positioned on said transverse supports for supporting the cereal above the base and channel, the channel and the space between the floor and base forming an air chamber, an air heater located externally of the housing, a blower, a casing enclosing the heater and connecting the blower with the air chamber below the perforated floor and including a tube having a reduced end leading directly into the said air chamber, an air return conduit connecting the top of the housing with the blower, means for causing air to be exhausted from the housing, means located in the housing in the path of air entering the return conduit controlling the last mentioned means when the saturation of the water vapor in the air has reached a predetermined degree, a fresh air intake in the return conduit, a valve normally closing said air intake and means set in operation by the controlling means for the air exhausting means for causing opening of the valve, the cereal being stored on the perforated floor so that the heated air is forced upwardly through said cereal to remove moisture, the floor sections being movable to discharge the cereal into the channel for removal therefrom.

WILLIAM A. NOEL.
